CLAIM

The ornamental design for a light as shown and described.

DESCRIPTION

FIG. 1 is a top perspective view of a light illustrating my new design.

FIG. 2 is a bottom perspective view thereof.

FIG. 3 is a top view thereof.

FIG. 4 is a bottom view thereof.

FIG. 5 is a right-side view thereof.

FIG. 6 is a left-side view thereof.

FIG. 7 is a front view thereof; and,

FIG. 8 is a rear view thereof.

Portions of the light are shown in broken lines. Portions shown in broken lines form no part of the claimed design. Portions of the light are shown with jagged broken lines. The appearance of any portion of the light between the jagged broken lines forms no part of the claimed design.

1 Claim, 8 Drawing Sheets
